CATALYTIC DESULFURIZATION OF PETROLEUM HYDROCARBONS IN A TWO STAGE AUTOFINING PROCESS

John Arthur Edgar Moy and John Rowland, Sunbury-on-Thames, England, assignors to The British Petroleum Company Limited, London, England, a British joint-stock corporation

No Drawing. Application March 21, 1956
Serial No. 572,785

Claims priority, application Great Britain March 22, 1955

6 Claims. (Cl. 208—210)

This invention relates to the catalytic desulfurization of petroleum hydrocarbons by means of the autofining process, the nature of which is described *inter alia* in United States Patents Nos. 2,573,726, 2,574,445—51 and 2,540,802. As set forth in these patents the autofining operation is carried out under a temperature selected between about 650°—800° F. and a pressure selected between 25—500 p.s.i. ga. with the temperature and pressure being correlated with respect to one another to insure a net production of hydrogen.

Almost complete desulfurization of the lower boiling petroleum distillates, such as naphtha and kerosene, is effected by once-through treatment of the distillate in the autofining zone, at a pressure of 100 lb./sq. in.

In order to achieve adequate desulfurization on a once-through basis of the higher boiling petroleum distillates, such as gas oils, however, it is generally necessary to carry out the process and operate the plant under the equilibrium pressure method described in United States Patent No. 2,648,623. The equilibrium pressure obtainable with any particular feedstock depends upon the particular catalyst employed, the temperature and the space velocity. For a given catalyst, temperature and space velocity, the equilibrium pressure gradually falls from the maximum obtainable with fresh catalyst to a lower value, with decrease in the catalyst activity. As set forth in Patent No. 2,648,623 in equilibrium pressure autofining, the temperature is selected between 650°—800° F. and the pressure is permitted to rise above 100 p.s.i. ga. until the amount of hydrogen produced equals the amount of hydrogen consumed at which point the system is in pressure equilibrium.

Plants suitable for the autofining of the lower boiling feedstocks may not necessarily be adapted for operation at the higher pressures reached when autofining under equilibrium pressure conditions, but it would nevertheless be desirable if the higher boiling petroleum distillates could be adequately desulfurized in such plants.

It has now been found that higher boiling petroleum distillates that are not adequately desulfurized by autofining on a once-through basis at pressures below the equilibrium autofining pressure of the distillate under the autofining conditions of catalyst, temperature and space velocity obtaining in the autofining zone, be further desulfurized by recycling or reprocessing the product obtained from the first treatment under substantially the same conditions.

According to the present invention therefore, a process for the catalytic desulfurization of a petroleum distillate, particularly of a higher boiling petroleum distillate that cannot be adequately desulfurized by autofining at pressures below the equilibrium autofining pressure, comprises autofining the distillate at a pressure below the equilibrium pressure and recycling the treated distillate to the reaction zone, or reprocessing the treated distillate,

2

preferably under the same conditions, over a fresh charge of catalyst.

The invention is particularly applicable to the autofining of gas oils.

The catalyst employed is preferably of the kind comprising the oxides of cobalt and molybdenum either as such or in combined form incorporated with a metal oxide support, usually alumina. The catalyst may with advantage comprise a small amount, preferably between 0.1% and 6.0% by weight, of fluorine as described in United States patent application Ser. No. 311,429, filed September 25, 1952, now U.S. Patent No. 2,800,429. The use of such a catalyst does not increase the degree of desulfurization unless equilibrium pressure operation is employed, but even at lower pressures it has the effect of producing a greater net yield of hydrogen which may with advantage be used in other processes in the refinery. The invention will now be described with reference to the following examples:

Example 1

A Kuwait gas oil was autofined in a pilot plant having a 100 ml. catalyst capacity under the following conditions:

Temperature	degrees F.	780
Pressure	p.s.i. ga.	100
Space velocity	v./v./hr.	2
Recycle rate	s.c.f./b.	2000
Duration	hours	40

30 The feedstock had the following inspection data:

S.G., 60° F./60° F.	0.8435	
I.B.P. (ASTM distillation)	degrees C.	248
F.B.P. (ASTM distillation)	degrees C.	360
Sulfur content	percent by weight	1.26
Br No.		3.7
Aromatics (ASTM D875)	percent by volume	14

The liquid product was washed with caustic soda solution and water to remove dissolved hydrogen sulfide and then reprocessed under the same conditions over a fresh charge of catalyst. Two types of catalyst were used, a catalyst consisting of the oxides of cobalt and molybdenum supported on alumina and a catalyst of similar composition but activated with aluminum fluoride.

45 The results were as follows:

50	Catalyst	Mixed Oxides of Cobalt and Molybdenum on alumina	Mixed oxides of Cobalt and Molybdenum on alumina activated with aluminum fluoride
Chemical Analysis, g./100 g. of material stable @ 1,020° F.:			
55	MoO ₃	15.75	14.4
	CoO	3.2	3.2
	F	0	3.36
Liquid Product inspection data After First Processing:			
55	S.G. 60° F./60° F.	0.8365	0.8390
	I.B.P. (ASTM), ° C.	110	104
	F.B.P. (ASTM), ° C.	354	355
60	Bromine No.	10.2	10.7
Aromatics (ASTM D875), percent			
60	vol	13.5	12.5
	Sulfur content, percent wt.	0.54	0.55
	Sulfur removal, percent	57	56
	Gross Hydrogen make, s.c.f./b.	115	136
Liquid Product inspection data After Second Processing:			
65	S.G. 60° F./60° F.	0.8350	0.8375
	I.B.P. (ASTM), ° C.	89	94
	F.B.P. (ASTM), ° C.	355	359
	Bromine No.	9.8	11.3
Aromatics (ASTM D875), percent			
70	vol	14.0	16.0
	Sulfur content, percent wt.	0.40	0.44
	Sulfur removal, percent	26	22
	Gross Hydrogen make, s.c.f./b.	28	41

Example 2

The same feedstock as in Example 1 was processed under the same conditions as in Example 1, using the catalyst that did not contain fluorine, for five processing periods, at the end of which the sulfur content of the product had been reduced to 0.17% wt. The results obtained were as follows:

Run number	1	2	3	4	5
Duration, hours	25	22	21	21	20
Sulfur content of product, percent wt.					0.17
Gross hydrogen make, s.c.f./b.	133	34	26	14	12

We claim:

1. A process for the catalytic desulfurization under autofining conditions of a petroleum distillate that cannot be adequately desulfurized under autofining conditions on a once-through basis at pressures below the equilibrium autofining pressure of the distillate obtainable under the autofining conditions of catalyst, temperature, and space velocity existing in an autofining zone, which comprises contacting the distillate in a reaction zone with a dehydrogenation-hydrogenation catalyst and hydrogen derived solely from the distillate at a temperature between about 650-800° F., and at a pressure below the equilibrium autofining pressure obtainable under the selected operating conditions, recovering a distillate of reduced sulfur content, passing the recovered distillate through a reaction zone as the sole feedstock therein and in contact with a dehydrogenation-hydrogenation catalyst and in the presence of hydrogen derived solely from the recovered distillate, and at a temperature between about 650-800° F. and at a pressure between about 25-500 p.s.i. ga., and recovering a distillate of still further reduced sulfur content from the product of the second operation.

2. A process in accordance with claim 1 wherein the

autofining conditions of the second stage reaction zone are substantially the same as the first stage reaction zone.

3. A process in accordance with claim 1 wherein the dehydrogenation-hydrogenation catalyst is oxides of cobalt and molybdenum on alumina.

4. A process in accordance with claim 3 wherein the catalyst contains about 0.1% and 6.0% of fluorine.

5. A process in accordance with claim 1 wherein the distillate is a gas oil.

10 6. A process for the catalytic desulfurization under autofining conditions of a petroleum distillate that cannot be adequately desulfurized under autofining conditions on a once-through basis at pressures below the equilibrium autofining pressure of the distillate obtainable under

15 the autofining conditions of catalyst, temperature, and space velocity existing in the autofining zone, which comprises contacting the distillate in a reaction zone with a dehydrogenation-hydrogenation catalyst and hydrogen derived solely from the distillate at a tem-

20 perature between about 650-800° F. and at a pressure below the equilibrium autofining pressure obtainable under the selected operating conditions, recovering a distillate of reduced sulfur content, recycling the recovered

25 distillate back to the first reaction zone as the sole feedstock therein and in contact with a fresh dehydrogenation-hydrogenation catalyst and in the presence of hydrogen derived solely from the recovered distillate, and under substantially the same conditions of temperature and pressure as the initial treatment, and recovering

30 a distillate of still further reduced sulfur content from the product of the second operation.
